UNITED STATES PATENT OFFICE.

ROSA D. HATCH, OF MEMPHIS, TENNESSEE

COMBINATION-TELEPHONE.

1,180,147.

Specification of Letters Patent. Patented Apr. 18, 1916.

Application filed March 15, 1915. Serial No. 14,445.

To all whom it may concern:

Be it known that I, ROSA D. HATCH, a citizen of the United States, residing at Memphis, in the county of Shelby and State 5 of Tennessee, have invented certain new and useful Improvements in Combination-Telephones; and I do hereby declare the following to be a full, clear, and exact description of the invention, such as will enable others skilled in the art to which it appertains to make and use the same, reference being had to the accompanying drawings, and to the letters and figures of reference marked thereon, which form a part 10 of this specification.

This invention relates to new and useful improvements in combination telephones and the object in view is to combine in one instrument both the transmitter and the 15 receiver.

The invention comprise various details of construction, combinations and arrangements of parts which will be hereinafter fully described, shown in the accompanying 20 drawings and then specifically defined in the appended claim.

My invention is illustrated in the accompanying drawings, in which:

Figure 1 is a side elevation of a combination telephone made in accordance with my invention. Fig. 2 is an end view looking at the transmitter and horn. Fig 3 is a central sectional view showing the switch mechanism for connecting the telephone and 35 throwing the same out of commission, and Fig. 4 is a sectional view on line 4-4 of Fig. 1 looking in the direction of the arrow.

Reference now being had to the details of the drawings by letter, A designates a 40 receiver of the usual construction of a telephone, and B is a horn which is connected thereto in any suitable manner, and C designates supporting wires which are fastened to the shank portion of the horn and which 45 support the transmitter D which is positioned centrally in front of the horn and adjacent to the end thereof. The trans-

mitter is connected to the telephone through the medium of the wires E, and F designates a hood which is preferably fastened 50 to the horn and affords means of privacy to the user of the telephone.

In order to regulate the size of the opening through the constricted portion of the horn, I provide an iris shutter, designated 55 in the drawings by letter I', which has a circumferential milled portion I², rotatable in the contracted portion I, as shown clearly in the drawings. By this provision of said iris shutter, the tone of the sound may be 60 regulated.

The switch mechanism for throwing on the currents consists of the terminals K and N, the former stationary and the latter yielding, and O is a switch member which 65 is pivotally mounted on the pin R and has two buttons, designated respectively by letters T and S, upon arms of said members, one of which buttons is adapted to be pushed upon for the purpose of closing the circuit 70 while the other breaks the circuit.

In operation, when it is desired to turn on the telephone, the operator presses down upon the button S, closing the circuit and which performs the same function that the 75 lifting of the ordinary receiver from the receiver holder upon telephones. The operator standing in front of the transmitter may talk into the same and, owing to the provision of the horn, the incoming message 80 may be distinctly heard without the necessity of the usual receiver, the hood about the horn serving to direct the vibrations to the ears of the person receiving the message 85 and at the same time prevent the message being heard at a distance from the telephone.

By the provision of an apparatus embodying the features of my invention, it will be noted that the telephone apparatus is greatly 90 simplified, the necessity of holding of the receiver to the ear by one hand being dispensed with as the lips of the person using the telephone may be positioned adjacent

thereto and the tone of the voice transmitted will, through the medium of the horn, be amplified.

What I claim to be new is:—

- 5 A combination telephone comprising a receiver with a horn fastened thereto, a wire fastened to the horn adjacent to its attachment to the receiver and bent about the end of the horn, a transmitter secured to
10 the end of the wire adjacent to the outer

end of the horn, a circuit closing switch upon the shank portion of the telephone, and a hood secured to and extending over the horn.

In testimony whereof I hereunto affix my 15
signature in presence of two witnesses.

ROSA D. HATCH.
